TABLE AND BOX CONVERTIBLE
STRUCTURE

Harvey G. Conner, Klamath Falls, Oreg.

Application August 30, 1948, Serial No. 46,733

2 Claims. (Cl. 311—90)

1

My invention relates to improvements in table and box convertible structures of the folding type for camping and like purposes, the primary object in view being to provide a simply constructed, inexpensive structure which is adapted to be easily and quickly converted into a table, or into a box for carrying food and other supplies to be used on the table.

Another object is to provide a structure of the type and for the purpose above set forth which will not collapse when used as a table nor accidentally unfold when used as a box and which may be strongly constructed without rendering the same heavy to carry when converted into a box.

Other and subordinate objects, within the purview of my invention, together with the precise nature of my improvements will be readily understood when the succeeding description and claims are read with reference to the drawings accompanying and forming part of the specification.

In said drawings:

Figure 1 is a view in perspective of my improved structure converted into a table with one extension panel detached;

Figure 2 is a fragmentary view in transverse section taken on the line 2—2 of Figure 1 and drawn to a larger scale;

Figure 3 is a view in bottom plan of the table top;

Fig. 4 is a fragmentary view in transverse section taken on the line 4—4 of Figure 1 and drawn to a larger scale;

Figure 5 is a fragmentary exploded view in perspective of one corner of the table top and one of the legs;

Figure 6 is a view in perspective of the box and top;

Figure 7 is a view in transverse section taken on the line 7—7 of Figure 6 and drawn to a larger scale;

Figure 8 is a fragmentary view in transverse section taken on the line 8—8 of Figure 6 and drawn to a larger scale;

Figure 9 is a fragmentary view in transverse section taken on the line 9—9 of Figure 10 and drawn to a larger scale;

Figure 10 is a view in perspective of the extension panels illustrating the manner in which the same are attached together;

Fig. 11 is a fragmentary view in vertical section taken on the line 11—11 of Figure 7.

Referring now to the drawings by numerals, the basic components of my improved structure

2

are a pair of elongated, box forming half sections 1 each embodying a pair of longitudinally related bottom and side panels 2, 3 respectively, and rectangular ends 4, said sections 1 being otherwise open. The sections 1 are wider than the depth thereof and the ends are hinged together, as at 5, at the ends of the sections and at corresponding corners of the ends 4 so that said sections 1 may be swung into edge to edge abutting relation to form an open box of a width equal to the combined width of the sections and providing a table top 6 of inverted box form with the side panels 3 and the ends 4 forming the sides and ends of said box, all as best shown in Figures 1, 2 and 3.

Right angled brackets 8 are provided in the corners of the sections 1 and legs 9 for slidably fitting in said brackets and corners to support the table top 6, said legs 9 being slidably detachable for a purpose presently seen.

Complemental lock bolt and keeper sections 10, 11 are set into abutting longitudinal edges of the bottom panels 2 of the sections 1 to be hidden from view and for key operation of the lock bolt section 10 to secure said sections 1 together in table top forming relation. A keyhole 12 is provided in one bottom panel 2 for a lock operating key not shown.

Suitable reinforcing and ornamenting cleats 13 may be provided on the ends 4 of the sections 1.

A pair of rectangular extension panels 14 are provided for attaching detachably to opposite sides of the table top 6 and which are of the same length as the bottom and side panels 2, 3, but, of the same width as the side panels 3, which is to say as the depth of the sections 1 for a particular purpose presently seen. The extensions 14 are each provided, for detachably attaching the same, with a pair of cross cleats 15 extending beyond one longitudinal edge thereof. The pairs of cross cleats 15 are adapted to be slid into pairs of apertures 16 provided in corresponding longitudinal edges of the side panels 3 so that said extension panels may be detachably attached to the table top 6 flush with the bottom panels 2 of the sections 1, which is to say with the top of the table top 6, and with said cleats bearing upwardly against the under faces of said panels 2 to maintain the extensions 14 horizontal.

The described table top 6 is adapted to be converted into a box, after the legs 9 and the extension panels 14 are detached, in the following manner. The sections 1 are swingable on the hinges

55

5 in edge to edge abutting relation from table top forming relation to form a box 17 of a width equal to twice the depth of said sections, as shown in Fig. 6, with the bottom panels 2 forming the sides of the box 17 and the side panels 3 forming the bottom of said box. Thus, the box 17 is rendered substantially narrower than the table top 6.

The extension panels 14 are attachable together with longitudinal edges abutting to form a top 18 for the box 17. For this purpose, one pair of the cleats 15 is spaced apart to fit between the other pair and the pairs of cleats 15 are provided with transversely bevelled sides 19 fitting together in pairs so that one pair of cleats is slidable endwise along the other with the cleats 15 of each extension panel 14 underlying the other extension panel 14 and the pairs of cleats 15 interlocked against lateral separation, thereby locking the extension panels 14 in coplanar edge to edge relation.

As previously explained, the extension panels 14 are of a width corresponding to the depth of the sections 1 so that the top 18 formed thereby provides a fitted top for the box 17.

One pair of cleats 15 is provided with end nubs 20 adapted to fit in sockets 21 in one of the panels 3 forming one side of the box 17 so that the nubs 20 may be inserted in the sockets 21 and the top then swung downwardly into closing position while interlocked at one longitudinal edge with one side of the box formed by the side panels 3 of one section 1. One extension panel 14 is provided in one longitudinal edge with a keeper lock section 22 for cooperation with the lock bolt section 10 to lock the top 18 in place when the sections 1 are swung, as described, to form the box 17, it being understood that in the box 17 the lock bolt section 10 is disposed at the top of one side of the box 17. Thus the top 18 for the box 17 may be locked closed by the same key as that used for locking the sections 1 in table forming relation.

A suitable latch 23 is pivoted, as at 24, on one side panel 3 forming the bottom of the box 17 and for swinging into cooperative relation to a pin 25 on the other side panel 3 to lock the sections 1 together in box forming relation. As will be seen, when the box 17 is formed, the before mentioned apertures 16 are disposed in the bottom of said box and the hinges 5 protrude above the top of said box. To accommodate the hinges 5 the extension panels 14 are provided with longitudinal, bevelled, end notches 26 in which said hinges 5 are seated when the top 18 is locked or closed.

It may be mentioned in passing, that the keeper section 11 is also disposed at the top of the box 17 when said box is formed but is, of course, not used. As may also be mentioned, when the sections 1 are in table forming relation, the latch 23 is disposed on one side panel 3 inside the table top 6 and concealed from view, the stud 25 being similarly located on the other side panel 3.

The foregoing will, it is believed, suffice to impart a clear understanding of my invention, without further explanation.

Manifestly, the invention, as described, is susceptible of modification, without departing from the inventive concept, and right is herein reserved to such modifications as fall within the scope of the appended claims.

Having described the invention, what is claimed as new is:

1. A table and box forming structure comprising a pair of elongated box forming sections each embodying a pair of right angularly related bottom and side panels, respectively, and a pair of rectangular ends, means pivotally connecting said sections together for relative swinging into edge abutting relation to form selectively a table top of inverted box form of a width corresponding to the width of both sections and a box of a width corresponding to the depth of both sections, legs attachable to said sections to support the same when forming a table top, a pair of extension panels attachable to the sections when formed into a table top, and means for attaching said extension panels together to form a top for the box formed by said sections comprising a pair of cross cleats on each extension panel, one pair slidably fitting between the other pair with the cleats on each panel overlapping and engaging the other panel, said cleats having beveled side edges coacting to hold said extension panels in a common plane.
2. A table and box forming structure comprising a pair of elongated box forming sections each embodying a pair of right angularly related bottom and side panels, respectively, and a pair of rectangular ends, said sections being wider than the depth thereof, respectively, means pivotally connecting said sections together for relative swinging into edge abutting relation to form selectively a table top of inverted box form of a width corresponding to the width of both sections and a box of a width corresponding to the depth of both sections, and extension panels attachable to the sections when formed into a table top and attachable together to form a top for the box formed by said sections, said bottom panels having locking devices thereon for securing said sections together when formed into a table top, and means for locking said extension panels when attached together to said box including a locking device coacting with one of the first mentioned locking devices.

HARVEY G. CONNER.
